UNITED STATES PATENT OFFICE.

WILLIAM A. LIGHTRALL, OF NEW YORK, N. Y.

IMPROVEMENT IN STEAM-BOILERS.

Specification forming part of Letters Patent No. 35,942, dated July 22, 1862.

To all whom it may concern:

Be it known that I, WILLIAM A. LIGHT-
HALL, of the city, county, and State of New
York, have invented a certain new and use-
ful Improvement in Steam-Boilers; and I do
hereby declare that the following is a full
and exact description of the same, reference
being had to the accompanying drawings, and
to the letters of reference marked thereon, in
which—

Figure 1 is a side elevation; Fig. 2, an end
elevation; Fig. 3, a central longitudinal sec-
tion, and Fig. 4 a central cross-section.

The nature of my invention consists in cre-
ating a forced and continued circulation of
the water contained in a steam-boiler through
the lower section of the series of the tubes of
the boiler, and from thence through the re-
maining sections of the series of the same to
the body of the boiler by means of a proper
force-pump operated by any required or de-
sired means, which receives the water from
the boiler at or about the coolest part of the
boiler and passes it rapidly and forcibly
through the said tubes in order that the evapo-
ration of the water may be increased (beyond
the amount that would be produced by the
natural and unforced circulation of the water
in the boiler) by such rapid and forced move-
ment of the water through the heated tubes
and by its constant and continued movement
and change of direction therein.

My invention is adapted to a great variety
of boilers; but the one presented in the accom-
panying drawings is preferred by me, for the
reason that the series of heating-tubes are so
arranged and attached to the body of the
boiler as to be readily detached and moved for
purposes of minute examination and repair,
while the body of the boiler affords sufficient
room for the quantity of water necessary to be
carried, and yet furnish active heating and
steam surfaces.

A is the body of the boiler, made in "wagon-
top" form (with side, front, and back legs as
shown) and having a "crown-sheet," B, ex-
tending from the front to the back leg of it.

C are the grate-bars, forming the base of the
furnace, which are equal in length to the
length between the front and back legs and of
width equal to the width between the side legs.

D are the furnace-doors, through which the
fuel is supplied to the furnace.

E is the series of six rows (in height) of
tubes, into which the water from the lower
portion of the side leg of the boiler is forced
by the force-pump F, the water from the pump
being first delivered into the cross-pipe G, and
after passing into and through the whole of
the first section of the series of tubes is then
forced and passed into the second, and so on
through the rest of the series until it is de-
livered into the cross-pipe H, from whence it
passes into the top portion of the boiler
through the connecting-pipes a a' a''. The first
of the series of tubes rests at its back end on
the bracket b, and the cross-pipes G and H are
so attached and connected with the boiler and
with the pipe c from the pump that by the re-
moval of their connecting-bolts the whole of
the series of tubes can be removed and taken
out for examination or repair.

The force-pump F can be operated either by
the main engine or by a separate engine, as
may be desired. In the latter case the engine
may also be used as a "pumping," a "blower."
or a "donkey" engine.

I is the smoke-stack, through which the pro-
ducts of combustion in the furnace pass off.

The fire in the furnace not only passes across
and among and between the tubes E, but
also acts with great force on the front, back,
and side legs of the boiler and upon the crown-
sheet B, so that the effect of the fuel in the
furnace is utilized to the greatest possible de-
gree before the waste gases and wasted pro-
ducts of combustion enter into and are car-
ried off through the smoke-stack I.

My invention is only applicable when fresh
water can be used in the boiler, as in cases
where salt-water or water containing sediment-
ary matter is used the deposition of salts or
sediment upon, around, and among the tubes
and upon the surfaces of the crown-sheet and
legs, would not only materially lessen their
effective action by the deposition resisting and
retarding the action of the heat upon them,
but would also tend to destroy them by the
corrosive action of these deposits upon them.

It will be apparent to practical engineers
that a great variety of modifications in the
forms of boilers and in the arrangement of the
heating-tubes can be made, while the essence
of my invention—the forced and continued
circulation of the water in the boiler over its
heating-surfaces—is preserved; and I do not,

therefore, confine myself to the application of the same to the form and arrangement of the boiler shown.

I claim, as advantages of the improvement herein set forth, that a boiler of given capacity can be made of less weight, will occupy less space, will cost less for its construction, will require less weight of water to be carried in it, will present greater evaporation (heating) surface, and therefore evaporate more water in the same space and with the same weight of boiler than any boiler now used.

I am aware that water has been forced by mechanical means into the heating-tubes of a boiler to produce rapid evaporation; but in all such cases the supply of water to be taken into and passed through the tubes was entirely received from and delivered by an external supply, the circulation in the boiler, if any, be-

ing entirely produced by and due to the difference in temperature between the coolest and hottest portions of the water in the same, differing therefore in principle and action entirely from my improvement of making that circulation dependent mainly upon its being forced and produced by mechanical means.

What I claim as my invention, and desire to secure by Letters Patent, is—

Producing a forced and continued circulation of the water in a steam-boiler, either through the tubes of the boiler or through and in the shell or body of the same, by mechanical means, as and for the purposes herein set forth.

WM. A. LIGHTHALL.
